UNITED STATES PATENT OFFICE.

ARTHUR E. THOMAS, OF WAYNE, MICHIGAN.

DESIGN FOR A DOOR LOCK.

Application filed December 14, 1927. Serial No. 24,481. Term of patent 14 years.

To all whom it may concern:

Be it known that I, ARTHUR E. THOMAS, a citizen of the United States, residing at Wayne, county of Wayne, State of Michigan, have invented a new, original, and ornamental Design for a Door Lock, of which the following is a specification, reference being had to the accompanying drawing, forming part thereof.

Fig. 1 is a front elevation.

Fig. 2 is a sectional view taken on line 2—2 of Fig. 1.

Fig. 3 is a side elevation.

I claim:

The ornamental design for a door lock, as shown.

ARTHUR E. THOMAS.
